[57] CLAIM

The ornamental design for a battery charger housing, as shown and described.

DESCRIPTION

FIG. 1 is an isometric view of a battery charger housing for a two-way communication device showing our new design; FIG. 2 is a front view thereof;

FIG. 3 is a left side view thereof;

FIG. 4 is a right side view thereof;

FIG. 5 is a top plan view thereof;

FIG. 6 is a rear view thereof; and,

FIG. 7 is a bottom plan view thereof.

The broken lines shown in FIGS. 1, 5 and 6 are included for the purpose of illustrating environmental elements only and form no part of the claimed design.
